UNITED STATES PATENT OFFICE.

MARTIN L. BEISTLE, OF SHIPPENSBURG, PENNSYLVANIA.

ORNAMENTAL BASKET STRUCTURE.

Application filed June 9, 1925. Serial No. 35,868.

This invention relates generally to articles formed by opening or expanding folded tissue forms and more particularly to a basket adapted to be folded to a relatively flat condition and to be expanded to form a basket filled with suitable objects.

The invention includes a basket handle member formed of cardboard stock, or the like, of suitably rigidity. The handle member is arranged to form a framework including portions that extend toward each other in the region of the base portion of the basket. On one side of one and the other side of the other of the inwardly directed extensions is mounted a foldable tissue member representing when expanded two semi-circular half portions of a basket. Each half basket portion is provided at its free end with a reinforcing member adapted to be hooked or otherwise attached to the opposite section of the handle member.

Another feature of the invention resides in the provision of foldable members representing objects such as eggs, baby chicks or the like, which can be expanded to occupy space within the basket, the members being attached to the handle or the extensions thereof.

It will be seen that an article of the general type described has been provided which normally folds to a flat condition and can be readily expanded to represent an ornamental basket filled with suitable objects.

Other features of the invention will be hereinafter referred to.

In the drawings, in which a preferred embodiment of the invention has been selected for illustration,

Figure 1 is a view in side elevation of an ornamental basket embodying the invention and shown in expanded or open condition.

Figure 2 is a view similar to Figure 1 showing the device in its folded condition.

Figure 3 is a view in side elevation of a frame member used in the construction of the device.

Figure 4 is a view in side elevation showing a pair of secondary frame or supporting members used in the construction of the device.

Figure 5 is a view showing a pair of end frame members for cooperation with the frame members shown in Figure 4.

Figure 6 is a view of an expansible paper tissue basket member shown in its folded condition.

Figure 7 is a perspective view of a folded tissue member which is adapted to be expanded to form an egg-like object.

Figure 8 is a sectional view taken on the line 8—8 of Figure 2.

Figure 9 is a detail showing the cellular construction of the expanded structure.

Referring to the drawings for a more detailed description of the invention, at 10 is shown a basket handle member formed of relatively rigid material such as cardboard. The handle member 10 is provided with inwardly extending portions 11 at the lower ends thereof which terminate at points relatively close to each other as at 12.

The inwardly directed terminal portions 11 of the handle 10 provide supports for an expansible member 13 formed of tissue paper, or the like, which is shown in a flat or folded condition in Figures 2 and 6 of the drawing. The member 13 is attached permanently in flat form at its central portion as at 14 to thereby provide a hinge about which the portions at either side of the clip 12 may be opened to provide a substantially circular structure as is shown in Figure 1 which represents a basket body portion.

It will be seen that the foldable member 13 is attached at one side to a face of the handle extension 11 and at the other side to the opposite face of the opposite handle extension portion 11. With this construction one-half of the member 11 may be opened out to provide a semi-circular section representing the one-half portion of a basket body member, the other member being expanded in like manner to provide the remaining half section and thereby complete the circle and produce a completed basket body section.

In order to hold the expanded portions in their unfolded condition, hook members 15 and 16 are provided in the handle member 10 and the frame members 17 which are attached to the unattached sides of the members 13 as is clearly shown in Figure 2 of the drawing. The hook members 15 and 16 are so formed as to be brought into attaching engagement with each other to complete the desired basket formation.

Not only is a basket-like structure provided by the expansible tissue member 13 but provision is also made for supplying objects to be placed or contained within the basket as in Figure 1 of the drawing. These ob-

jects or articles may simulate eggs, chicks or the like and are preferably formed of expandible tissue in a similar manner to that employed in the construction of the basket body portion 13.

Each member 17 carries at its inner end an upward extension 19 along the upper edge of which is fastened one side of a semi-circular folded member 18. A frame member 20 is attached to the outer side of the folded member 18 in such a manner that it can pivot about the side 24. Folded members 25 and 26, similar to member 18, are fastened between frame members 19 and 20 along sides adjacent to the pivoted sides. In order to expand the members 18, 25 and 26 the tab 27 formed on the lower side is lifted upwardly, causing the frame member 20 to pivot about the side 24. As the frame member 20 moves toward a position vertically above, and in the same plane with, extension 19 the members 25 and 26 are spread out fan-wise in planes at right angles to the extension 19. As the member 20 is inclined further toward the rear the members 25 and 26 bend around over the sides of members 19 and 20, until when the frame member 20 comes to rest in contact with the rear side of extension 19, the members 25 and 26 have assumed the shape of eggs 28 and 29. Meanwhile member 18 has expanded into egg 21.

A further addition to the device may take the form of members 22 preferably formed integrally with the handle member 10 and representing chick-like objects. In like manner a card 23 may be formed integrally with the handle member 10.

It will be seen that an ornamental basket has been provided which normally is folded in a flat condition to render it convenient for shipping or storage and which can be easily expanded to provide the ornamental article described. The cellular structure of the expanded basket and egg-like members is of itself attractive and the device as a whole is designed to provide an interesting and attractive toy or ornamental device. While the particular device illustrated and described represents an Easter basket it will be clear that many departures may be made from the precise construction shown but without exceeding the scope of the appended claims.

I claim:—

1. An ornamental article comprising a non-folding base, a member formed of folded tissue extending through the base and attached to the base in such a manner that when expanded it simulates a continuous article about said base.

2. An ornamental article comprising a base, and a member formed of expandible tissue and attached in a non-expanded condition to opposite sides of said base.

3. An ornamental article comprising a

non-folding base, and a member formed of expandible tissue and attached in a non-expanded condition to opposite sides of said base.

4. An ornamental article comprising a base, a member formed of folded tissue and extending through an opening in the base and attached to opposite sides of the base.

5. An ornamental article comprising a non-folding base, a member formed of folded tissue and attached to the base with opposite sides of the member in contact with opposite sides of the base.

6. An ornamental article comprising a non-folding base, a member formed of folded tissue and expandible in opposite directions from the center thereof to form a body, said member being so attached to the base that when expanded each half of the member will form half of the body.

7. In an ornamental basket, a non-folding handle member formed of relatively rigid material and having portions extending toward each other at the lower ends thereof, a foldable tissue member attached at one end to one side of one of the handle extension members and at the other end to the other side of the other handle extension member, said foldable tissue member being formed and arranged to simulate a basket when unfolded.

8. In an ornamental basket, a non-folding handle member formed of relatively rigid material and having portions extending toward each other at the lower ends thereof, a folded tissue member clamped at its central portion to form a hinge and attached at its opposite ends to opposite sides of the extended handle portions, reinforcing members attached to the free faces of the tissue members, and inter-engaging hook members on the handle member and the reinforcing member for holding the foldable tissue member in an expanded condition.

9. An ornamental basket comprising a flat base, a basket body formed of expandible tissue, and ornamental objects within said body, said objects being formed of expandible tissue and being expandible independently of the body.

10. An ornamental basket comprising a flat base, a basket body formed of expandible tissue, two frame members within the body and pivotal independently about each other, and a plurality of expandible members carried by the frame members and adapted to form a plurality of ornamental objects.

11. In an ornamental basket structure, a handle member formed of relatively rigid sheet material, a basket body portion formed of folds of tissue material, foldable tissue members simulating eggs, and book-like cover members for enclosing a group of said members when folded, the cover mem-

bers being adapted to be opened to produce the egg-like members.

12. In an ornamental article, a frame member, a second frame member adapted to 5 pivot about the first frame member, a member formed of folded tissue and attached to each frame member along its pivoted side, and a second member formed of folded tissue and attached to each frame member in 10 angular relation to the pivotal side.
13. In an ornamental article, a frame member, a second frame member adapted to pivot about the first frame member, a member formed of folded tissue and attached to 15 each frame member along its pivoted side,

and a second member formed of folded tissue and attached to each frame member along a side located in angular relation to the pivotal side.

14. In an ornamental article, reversible 20 book-like cover members inclosing a plurality of folded tissue members, the tissue members being so related to the cover members that opening the book-like covers will expand the tissue members into a plurality 25 of ornamental objects lying along axes angularly related to each other.

In testimony whereof I affix my signature.

MARTIN L. BEISTLE.
